DENTAL EQUIPMENT STAND

Robert S. Wyne, Kansas City, Mo.

Application January 6, 1951, Serial No. 204,708

7 Claims. (Cl. 32—22)

1

This invention relates to dental apparatus and more particularly to a high volume water takeoff and blood ejector or siphon pump attachment operated thereby for use on conventional dental unit pedestals having fountain cuspidors and water supply and discharge connections.

Conventional dental units having a cuspidor on an apparatus pedestal, a water supply unit enclosed in the pedestal, a saliva ejector and various valve controlled flow lines or passages for desired operation of the unit. A saliva ejector is usually sufficient for normal or general dental requirements, but when dental surgery is necessary other equipment must be moved in or the patient taken to other rooms having surgical equipment because the conventional dental unit and particularly the saliva ejector is not capable of handling the quantity of blood resulting from surgery.

The objects of the present invention are to provide apparatus which is an accessory or improvement for dental units to adapt same for the handling of blood from dental surgery without detracting from the normal operation of the unit and conventional apparatus thereon; to provide a high volume water takeoff for dental units; to provide a blood ejector operated by the high volume water takeoff; to provide a blood ejector assembly and discharge therefor removably mounted in the conventional cuspidor without alteration of the conventional apparatus and operation of the dental unit; and to provide a simple, efficient attachment to conventional dental units for handling blood resulting from dental surgery that is economical to manufacture and easily applied to the dental units.

In accomplishing these and other objects of the present invention, I have provided improved details of structure, the preferred forms of which are illustrated in the accompanying drawings, wherein:

Fig. 1 is an elevational view of the high volume water takeoff and blood ejector mounted on a conventional dental unit.

Fig. 2 is a vertical sectional view through a portion of the dental unit with the high volume water takeoff attached thereto.

Fig. 3 is a disassembled perspective view of the parts of the high volume water takeoff.

Fig. 4 is a transverse sectional view through the high volume water takeoff on the line 4—4, Fig. 2.

Fig. 5 is a vertical sectional view through the blood ejector.

Fig. 6 is a sectional view through a modified form of high volume water takeoff attached to a dental unit pedestal.

2

Referring more in detail to the drawings:

1 designates a dental unit including a support 2 in the form of a dental stand or pedestal and having a laterally projecting portion 3 on which 5 is secured a mounting or bearing 4 designed to rotatably receive and support a tubular member in the form of an arm 5 having thereon a cuspidor bowl or basin 6 communicating therewith. Supported on the inner end of the tubular member is 10 a hollow, upstanding arm 7, the upper end of which is enlarged to form a head 8 enclosing suitable valves (not shown) controlling flow of water to a nozzle tube 9 of a tumbler holder 10 carried on a reduced extension 11 of the upstanding arm 7, the valves and the head also controlling flow of water through a saliva ejecting means housed within the head and from which extends a flexible conduit 12 carrying the usual or any suitable terminal (not shown) for insertion with- 15 20 in the patient's mouth for withdrawing the saliva. A liquid supply conduit 13 leading to the valve head 8 has an inlet end connected with a coupling 14 which in turn is detachably connected by a nut 15 with a reduced extension 16 on the lower end 25 of the bearing 4. The extension is provided with an outlet passage 17 communicating with a valve chamber 18 having an inlet passage 19 adapted to be controlled by a master valve 20 disposed within said chamber. Leading to the inlet pas- 30 sage 19 is a supply pipe or connection 21 disposed within the hollow pedestal and adapted to receive a supply from a suitable source (not shown). The valve 20 serves to control the water supply for the cuspidor and glass holder and is 35 intended to be closed when the apparatus is not in use.

The liquid supplied to the cuspidor is adapted to discharge therefrom into the tubular arm 5 from whence it passes through the reduced outlet portion 22 of the arm to the passage 23 of the bearing 4 and into a pipe 24 connected with said passage and extending within the pedestal and adapted to convey the liquid therefrom to a suitable discharge pipe (not shown). The above de- 40 scribed structure is conventional and usually includes a master valve bonnet mounted on the bearing 4 supporting a valve stem and external master valve operating member for controlling flow of liquid from the inlet passage 19, said liquid normally flowing only to the outlet passage 17 and conduits connected therewith.

The master valve having a high volume water take-off and forming part of the invention includes a body member 25, cylindrical in cross-section, having an externally threaded end 26 screwed into a threaded bore 27 forming part of

the valve chamber 18 whereby a longitudinal bore 28 of the valve body 25 communicates with the valve chamber 18. The end of the valve body 25 remote from the threaded end 26 is provided with a polygonal-shaped head 29 for facilitating threading of the valve body into the threaded bore 27. The valve body head includes a cylindrical collar 30 larger in diameter than an adjacent integral collar 31 which in turn is larger in diameter than the tubular portion 32 of the valve body to form shoulders 33 and 34. The head end of the valve body is provided with a threaded counter-bore 35 into which is screwed the threaded shank 36 of a bonnet 37. The shank 36 is smaller in diameter than the adjacent portion of the bonnet to provide a shoulder 38 whereby a gasket 39 is compressed between the shoulder 38 and the end face of the head end of the valve body to make a watertight joint.

The bonnet is provided with a threaded bore 40 engaging an externally threaded portion 41 of a valve stem 42 which extends through the bonnet and valve body and carries the master valve 20 on one end thereof. The other end of the stem is provided with a valve operating member 43 whereby rotation of the member 43 screws the stem in the threaded bore 40 to move the valve 20 toward or away from the valve seat 44 surrounding the inlet passage 19. The bonnet is provided with suitable packing 45 and a packing gland 46 for preventing leakage around the valve stem. A sleeve member 47 is provided with axial bores 48 and 49 adjacent the respective ends thereof and slidably engaged with the peripheries in the collar 31 and tubular member 32 respectively, a gasket 50 being interposed between the end of the sleeve member and the face of the bearing member 4 surrounding the threaded bore 27 and a gasket 51 being interposed between the other end of the sleeve member and the shoulder 33 on the valve body whereby threading of the valve body into the threaded bore 27 compresses the gaskets 50 and 51 to form watertight joints.

The sleeve member 47 has an enlarged intermediate portion forming an annular chamber 52 surrounding the tubular portion 32 of the valve body, said annular chamber having communication with the valve body bore 28 through passages 53. The sleeve member 47 has a lateral extension 54 provided with a bore 55 communicating with the annular chamber 52. A control valve 56 is suitably connected with the extension 54 and has a valve chamber 57 with an inlet passage 58 adapted to be controlled by a valve 59 disposed within said chamber and having an operating portion 60, said inlet passage 58 having communication through the bore 55 with the annular chamber 52. The operating portion 60 is fixed on a valve stem 61 which carries the valve 59, said stem having a threaded portion 62 screwed into a threaded bore 63 of a bonnet 64 provided with suitable packing 65 and packing gland 66 to prevent leakage around the valve stem. The control valve 56 has a lateral member 67 provided with an outlet passage 68 communicating with the valve chamber 57. The lateral member 67 is connected by a suitable fitting 69 with a tube 70 whereby the bore 71 of said tube has communication with the outlet passage 68 for flow of water to a blood ejector generally designated 72.

The blood ejector includes a body member 73 having a chamber 74 communicating with the passage 75 of a liquid discharge tube 76 having a terminal end 77 connected by a union nut 78 to

the body member 73 to form a watertight connection thereto. The tube 76 is preferably formed of metal and so shaped that the terminal end 77 is in axial alignment with the throat 79 forming the drain opening of the cuspidor bowl 6 and the other end of said tube 76 extending downwardly exteriorly of the cuspidor bowl 6 and suitably fixed to a bracket 80 carried by a resilient metal clamp 81 adapted to engage a periphery of the cuspidor bowl to support the bracket thereon. Said other end of the tube 76 is connected by a suitable fitting 82 with the flexible tube 79 to provide communication between the respective passages thereof for supply of water to the chamber 74 of the blood ejection body member 73. Connected to the blood ejection body member 73 is a connection 83 sleeved over and suitably secured to an extension 84 of the body member 73, said extension having a relatively small bore 85 at its inlet end and an enlarged bore 86 at its discharge end, the small bore 85 extending through a projection 87 of reduced diameter and extending into the enlarged bore 86 to form a nozzle. A side aperture 88 is provided into the enlarged bore 86 adjacent the nozzle and the connection which forms an annular chamber 89 around the extension 84 communicating with the aperture 88.

A flexible tube 90 is connected at one end to a tubular fitting 91 secured to the connection 83 and having communication with the annular chamber 89. The other end of the tube 90 is equipped with a terminal 92 of suitable structure for insertion into a patient's mouth for drawing therefrom blood resulting from dental surgery. A tube 93 has its upper end secured to the connection 83 whereby the passage 94 of said tube 93 communicates with the enlarged bore 86. The lower end of tube 93 is provided with an enlarged member 95 provided with a depending circular flange 96, the lower edge of which is adapted to seat in a cuspidor opening 79. A plurality of apertures 97 are provided in the depending flange 96 for flow of liquids from the cuspidor bowl 6 into the drain opening 79 for normal use of said cuspidor bowl. The seating of the lower edge of the depending flange 96 in the cuspidor bowl and the engagement of the clamp 81 to support one end of the tube 76 provides a mounting for the blood ejector 72 which permits same to be left in place at all times if desired. However, the blood ejector and all tubular connections therefor may be quickly removed by merely disengaging the clamp 81 from the cuspidor bowl and lifting the blood ejector apparatus therefrom.

The bracket 80 is preferably provided with a suitable device 98 for supporting the terminal 92 when the blood ejector is not in use. The chamber 74 of the blood ejector body member is preferably provided with a suitably curved baffle 99 to provide a whirling motion to the water passing through the chamber and the small bore 85. When the apparatus is not in use the valve 20 and valve 59 should be in closed position. When the apparatus is to be used for ordinary dental work, the valve operating member 43 is rotated to screw the stem 42 in the threaded bore 40 to move the valve 20 away from the seat 44 permitting flow of water from the supply pipe 21 through the inlet passage 19, valve chamber 18, outlet passage 17, coupling 14, conduit 13, to the head 8. Then by operating the valves in the head 8 the water may flow from the tube 9 and also through the saliva ejector to provide a saliva suction in the tube 12.

When dental surgery is to be performed, the

valve 20 being in open position, operation of the valves operating member 60 to open the valve 59 allows water to flow from the valve chamber 18 through the bore 28, passages 53, annular chamber 52, bore 55, inlet passage 58, valve chamber 57, outlet passage 68, tube bore 71, bore 75, to the chamber 74, where the baffle 99 provides a whirling action to the water passing through the small bore 85. The jet of water issuing from the small bore 85 into the enlarged bore 86 from whence it flows through the bore 94 through the discharge opening 79 of the cuspidor bowl 6, through the hollow arm 5, reduced neck 22, passage 23 and pipe 24 for disposal. The jet of water issuing from the small bore 85 reduces the pressure in the annular chamber 89 which effects a suction in the tube 90. Due to the large volume of water flowing through the high volume water takeoff, the suction is sufficient that when the dental surgery is being performed and the terminal end 92 in the patient's mouth, the large quantity of blood resulting from the surgery will be drawn through the terminal 92, tube 90, chamber 89, through the aperture 88 and discharged with the water through the enlarged bore 86, bore 94 to the drain of the cuspidor. The arrangement is such that there is no tendency for back pressure to be created sufficient to effect flow of water into the tube 90.

When the dental surgery is completed, the valve 59 is closed, stopping flow of water to the blood ejector but permitting the normal use of the remainder of the apparatus carried on the pedestal 1. If desired, the blood ejector mechanism can be removed from the cuspidor bowl but it can be also left in place without interfering with the normal operations of the pedestal apparatus.

A modified form of master valve structure having a high volume water takeoff is shown in Fig. 6, this form of the invention being designated for use on pedestals wherein the bearing 4 has an externally threaded boss 100 provided with a bore 101 communicating with the valve chamber 18. In such structures a valve body 102 is connected to the threaded boss 100 by means of a union nut 103. The body 102 has a chamber 104 communicating through a bore 105 with the bore 101 and the valve chamber 18. The valve 20 is carried on a stem 106 having a threaded portion 107 screwed into an internally threaded bore 108 in the valve body 102, said stem having an external operating member 109. The valve body is provided with suitable packing 110 and a packing gland 111 to prevent leakage around the valve stem. The body 102 has a lateral extension 112 which is suitably connected to the control valve 56, whereby the inlet passage 58 of said control valve communicates through an aperture 113 with the chamber 104.

The operation of the structure with this modified form of master valve is the same as was described in connection with the structure illustrated in Figs. 1 to 5, inclusive.

It is believed obvious that I have provided a blood ejector mechanism and high volume water takeoff therefor for a conventional dental pedestal for adapting same for use in dental surgery without altering the conventional operation of the pedestal apparatus.

What I claim and desire to secure by Letters Patent is:

1. In dental apparatus having a hollow pedestal with a cuspidor, saliva ejector and water supply and discharge connections, said cuspidor having a drain communicating with the dis-

charge connections, said pedestal having a valve chamber and inlet and outlet passages therein communicating with said valve chamber, said outlet passage having valved connection with the saliva ejector, a valve body mounted on the pedestal and having a bore coaxial with said inlet passage, a valve stem extending through the valve body and into the valve chamber, means on said stem for controlling flow of water from the inlet passage into the valve chamber, means in the valve body engaging the valve stem remotely of the pedestal for preventing leakage of water around said stem, a valve controlled flow line connected to the valve body and communicating with the bore therein for supplying a high volume water takeoff therefrom, and a blood ejector operatively connected with the flow line.

2. In dental apparatus having a hollow pedestal with a cuspidor, saliva ejector and water supply and discharge connections, said cuspidor having a drain communicating with the discharge connections, said pedestal having a valve chamber and inlet and outlet passages therein communicating with said valve chamber, said outlet passage having valved connection with the saliva ejector, a valve body mounted on the pedestal and extending therefrom, said valve body having a bore coaxial with said inlet passage and communicating with the valve chamber, a valve stem extending through the valve body and into the valve chamber, a valve on said stem for controlling flow of water from the inlet passage into the valve chamber, means in the valve body engaging the valve stem remotely of the pedestal for preventing leakage of water around said stem, a valve controlled flow line connected to the valve body and communicating with the bore therein for supplying a high volume water takeoff therefrom, a blood ejector operatively connected with the flow line, and a discharge pipe for said blood ejector discharging into the cuspidor drain.

3. In dental apparatus having a hollow pedestal with a cuspidor and water supply and discharge connections, said cuspidor having a drain communicating with the discharge connections, a valve body mounted on the pedestal and having a chamber communicating with the water supply, valve means in the valve body and extending into the pedestal for controlling the water supply, a blood ejector having a discharge nozzle therein, a discharge pipe secured to the ejector, an apertured end on the discharge pipe seated in the cuspidor drain for supporting the discharge pipe and ejector, said apertured end providing drainage from the cuspidor, means removably mounted on the cuspidor and engaging the ejector for supporting the upper end of same over the cuspidor, valve controlled means connected to the valve body and the blood ejector for flow of water from the chamber in the valve body to the ejector, and a fitting adapted for insertion in a patient's mouth and having communication with the ejector adjacent the nozzle therein whereby discharge of water from the nozzle will form a suction drawing blood and liquids from the patient's mouth and discharge same into the cuspidor drain.

4. In dental apparatus having a hollow pedestal with a cuspidor and water supply and discharge connections, said cuspidor having a drain communicating with the discharge connections, a valve body mounted on the pedestal and having a chamber communicating with the water supply, valve means in the valve body and extending into the pedestal for controlling the

water supply, a blood ejector having a discharge nozzle therein, a discharge pipe secured to the ejector, an apertured end on the discharge pipe seated on the cuspidor around the drain thereof for supporting the discharge pipe and ejector and providing for drainage from the cuspidor, a bracket supported on the cuspidor, a tube having one end fixed on the bracket and the other end connected to the ejector for supporting the upper end of same, said tube communicating with the ejector for supplying water thereto, valve controlled means connected to the valve body and said one end of the tube for flow of water from the chamber in the valve body to the ejector, and a fitting adapted for insertion in a patient's mouth and having communication with the ejector adjacent the nozzle therein whereby discharge of water from the nozzle will form a suction drawing blood and liquids from the patient's mouth and discharging same into the cuspidor drain.

5. In dental apparatus having a hollow pedestal with a cuspidor, saliva ejector and water supply and discharge connections, said cuspidor having a drain communicating with the discharge connections, said pedestal having a valve chamber and inlet and outlet passages therein communicating with said valve chamber, said outlet passage having valved connection with the saliva ejector, a valve body mounted on the pedestal and having a bore coaxial with said inlet passage, means extending through the valve body and into the valve chamber for controlling flow of water from the inlet passage into the valve chamber, a valve controlled flow line connected to the valve body and communicating with the bore therein for supplying a high volume water takeoff therefrom, a blood ejector having a discharge nozzle therein, means removably mounted on the cuspidor and engaging the blood ejector for supporting the upper end of same over the cuspidor, said valve controlled flow line being connected with the blood ejector for flow of water from the valve body to the blood ejector, and a fitting adapted for insertion in a patient's mouth and having communication with the blood ejector adjacent the nozzle therein whereby discharge of water from the nozzle will form a suction drawing blood and liquids from the patient's mouth and discharging same into the cuspidor drain.

6. In dental apparatus having a hollow pedestal with a cuspidor, saliva ejector and water supply and discharge connections, said cuspidor having a drain communicating with the discharge connections, said pedestal having a valve chamber and inlet and outlet passages therein communicating with said valve chamber, said outlet passage having valved connection with the saliva ejector, a valve body mounted on the pedestal and extending therefrom, said valve body having a bore coaxial with said inlet passage and communicating with the valve chamber, a valve stem extending through the valve body and into the valve chamber, means on said stem for controlling flow of water from the inlet passage into the valve chamber, means in the valve body engaging the valve stem remotely of the pedestal for preventing leakage of water around said stem, a valve controlled flow line connected to the valve body and communicating with the bore therein for supplying a high volume water takeoff there-

5 from, a blood ejector having a discharge nozzle therein, a discharge pipe for said blood ejector discharging into the cuspidor drain, an apertured end on the discharge pipe seated in the cuspidor drain for supporting the discharge pipe and blood ejector, means removably mounted on the cuspidor and engaging the blood ejector for supporting the upper end of same over the cuspidor, said valve controlled flow line being connected with the blood ejector for flow of water from the valve body to the blood ejector, and a fitting adapted for insertion in a patient's mouth and having communication with the blood ejector adjacent the nozzle therein whereby discharge of water from the nozzle will form a suction drawing blood and liquids from the patient's mouth and discharging same into the cuspidor drain.

7. In dental apparatus having a hollow pedestal with a cuspidor, saliva ejector and water supply and discharge connections, said cuspidor having a drain communicating with the discharge connections, said pedestal having a valve chamber and inlet and outlet passages therein communicating with said valve chamber, said outlet passage having valved connection with the saliva ejector, a valve body mounted on the pedestal and extending therefrom, said valve body having a bore coaxial with said inlet passage and communicating with the valve chamber, a valve stem extending through the valve body and into the valve chamber, a valve on said stem for controlling flow of water from the inlet passage into the valve chamber, means in the valve body engaging the valve stem remotely of the pedestal for preventing leakage of water around said stem, a valve controlled flow line connected to the valve body and communicating with the bore therein for supplying a high volume water takeoff therefrom, a blood ejector having a discharge nozzle therein, a discharge pipe for said blood ejector discharging into the cuspidor drain, a depending flanged end on the discharge pipe with the edge of the flange seated in the cuspidor drain for supporting the discharge pipe and blood ejector, said depending flange having a plurality of apertures for drainage from the cuspidor, a bracket fixed on the cuspidor, a tube having one end supported on the bracket and the other end connected to the blood ejector for supporting the upper end of same, said one end of the tube being connected to the valve controlled flow line and the other end communicating with the blood ejector for flow of water from the valve body to the blood ejector, and a fitting adapted for insertion in a patient's mouth and having communication with the blood ejector adjacent the nozzle therein whereby discharge of water from the nozzle will form a suction drawing blood and liquids from the patient's mouth and discharging same into the cuspidor drain.
